UNITED STATES PATENT OFFICE.

HEINRICH STOLL, JR., OF REUTLINGEN, GERMANY.

CIRCULAR INDEPENDENT-NEEDLE KNITTING-MACHINE.

No. 867,764.

Specification of Letters Patent.

Patented Oct. 8, 1907.

Application filed October 14, 1905. Serial No. 282,867.

To all whom it may concern:

Be it known that I, HEINRICH STOLL, Jr., a citizen of the German Empire, residing at Reutlingen, in the Kingdom of Würtemberg, Germany, have invented certain new and useful Improvements in Circular Independent-Needle Knitting-Machines, of which the following is a description, reference being had to the accompanying drawing, and to the letters and figures of reference marked thereon.

This invention relates to knitting machines of that general class in which double ended needles are employed on two superposed cylinders or other carriers and are transferred from cylinder to cylinder during the knitting operation.

One of the principal objects of the invention is to provide a machine in which a jacquard or similar pattern mechanism is employed to control the movements of the needles and the general design or pattern of the work.

A further object of the invention is to so arrange the mechanism that different groups of needles are held in operation in successive order to permit the selective movement of the pattern mechanism.

A still further object of the invention is to provide for the division of the needles and the pattern devices into a corresponding number of groups each including a card cylinder or like member.

A still further object of the invention is to provide a machine by which patterned fabric, plain, purled and one and one (ribbed) fabric may be produced.

The invention consists in the matters hereinafter described and referred to in the claims.

In the accompanying drawings:—Figure 1 is a development of the two cylinders and cams, showing a portion of the pattern mechanism in elevation. Fig. 2 is a plan view showing the sectional pattern mechanism, the latter in this instance being divided into four parts. Fig. 3 is a vertical section of the machine. Fig. 4 is a development of the machine (partly contracted in width) showing the adjustment of the parts for the manufacture of smooth goods. Figs. 4^a and 4^b are sectional views of the cylinders on the corresponding marked section lines Fig. 4, the cams being omitted. Fig. 5 is a view similar to Fig. 4, the machine being arranged for the manufacture of left and left goods. Figs. 5^a and 5^b are sectional views of the cylinders on the correspondingly marked section lines Fig. 5, the cams being omitted. Fig. 6 is a view corresponding to Fig. 4, showing the machine arranged for the manufacture of one and one goods. Figs. 6^a and 6^b are sectional views of the cylinders on the correspondingly marked section lines of Fig. 6, the cams being omitted. Fig. 7 is a view corresponding to Fig. 4, showing the machine arranged to manufacture figured goods. Figs. 7^a and 7^b are sectional views of the cylinders on the correspond-

ingly marked section lines Fig. 7, the cams being omitted. Fig. 8 is a sectional view of the cylinders on the line 8—8 of Fig. 9. Fig. 9 is a development similar to Fig. 1, showing the mesh forming operation, in this instance for the production of one and one goods. 60

Similar reference characters throughout the specification and drawings indicate corresponding parts.

The two cylinders *a*, *a'* have their axes in the same vertical plane and are supported in superposed relation as usual and at points near their adjacent ends are inclined flanges or cams *y*—*y'* which serve in the usual manner to deflect the jacks outward and free the needles. The cylinders are stationary and around them revolve the lower and upper cam rings 10, 11, and above the upper cam ring is a jacquard or pattern mechanism *J* for controlling the character of fabric produced. 65

The lower cam groove *v*, *v'* is continuous and the feet of the lower jacks *b* are in constant engagement therewith while the shape or contour of the cam is such as to effect vertical movement of the jacks in moving the needles *c*. 70

Between the main operating portions *o*, *q* and *k* of the lower cam the groove *v'* is horizontal and is so arranged that the jacks *b* and the needles are retained inoperative in the lower cylinder and the length of this portion 80 of the cam groove is equal to or greater than the width of any one of the sections into which the jacquard or pattern mechanism is divided, as will hereinafter appear.

The cams *o'*, *r*, *p*, *k'* and *q'* of the upper cam ring 11 85 operate on the feet of the upper jacks *b'* in the manipulation of the needles *c*, the feet of the jacks traveling in the groove *w*. Between the cam *p* and the cam *k'* however, the top of the cam groove is open and when the top of the cam *p* passes from under the feet of the upper jacks the latter are elevated to such an extent 90 that they cannot be engaged by the cam *k'* and again drawn down into the groove. The jacks when raised to this position are held up by small leaf springs *g* carried by the upper cylinder. 95

The distance between the cams *p* and *k'* is greater than the width of one of the sections into which the jacquard or pattern mechanism is divided and this idle portion of the upper cam is above the idle portion *v'* of the lower cam in order to permit the operation of such 100 jacquard mechanism.

In the jack or needle grooves of the upper cylinder are arranged auxiliary jacks *d*, the lower ends of which may be forced into engagement with the upper ends of the main jacks *b'* in order to so depress the latter that 105 their feet may be caught by the cam *k'*. The feet of the auxiliary jacks are under the control of an auxiliary cam *i* that is secured to and travels with the upper cam ring, this cam *i* being disposed in a vertical plane in advance of the vertical plane of the cam *k'* so that 110

when the auxiliary jacks are forced down by the cam *i* the feet of the main jacks *b'* are depressed to such a position that they may be caught by the cam *k'*.

The auxiliary jacks are under the direct control of 5 the jacquard mechanism and this mechanism by raising the feet of the predetermined jacks out of the path of the cam *i*, will control the character and pattern of goods produced. If the pattern mechanism raises an auxiliary jack out of the path *v*, the corresponding main 10 jack is held up out of needle engaging position and the corresponding needle remains in the lower cylinder.

The jacquard mechanism is shown in the present instance as divided into four equal sections, although there may be more or less sections as dictated by the 15 size of the machine.

The sectional jacquard is stationary and is supported from the main post of the machine while the upper cam ring carries a revolute cam *x* for actuating the jacquard. Each section includes a card cylinder of ordinary 20 construction and a number of jack needles *f* corresponding to one fourth the number of auxiliary jacks *d* and these needles are connected to the auxiliary jacks *d* by cords *h* which pass through suitable guiding eyes.

The card cylinders are moved in successive order 25 against their respective needles by means of the cam *x* Figs 2 and 3 and those needles *f* opposite the unperforated portions of the cards are thrust back toward the axes of the cylinders thereby raising the auxiliary jacks to which they are connected and insuring the retention 30 of the corresponding main jacks in elevated, inoperative position.

All of the auxiliary jacks elevated by the pattern mechanism are depressed by a cam *z* once in each revolution of the machine.

35 In the manufacture of plain fabrics the upper jacks assume the position shown in Fig. 4, all of said jacks remaining inoperative as in this method of knitting the meshes are cast off only from the lower cylinder.

In the manufacture of purled or through and through 40 fabric all of the upper jacks are depressed by the cams *i* and *k'* and all of the needles are transferred from cylinder to cylinder.

In the manufacture of one and one (ribbed) goods as 45 shown in Fig. 6, and patterned goods as shown in Fig. 7, the jacquard mechanism comes into play and each section of the jacquard acts in turn on the group of needles under its control while such needles and their jacks are in the idle portions of the cams as previously described.

Having thus particularly described my invention, 50 what I claim as new and desire to secure by Letters Patent, is:—

1. The combination with a knitting machine, of a jacquard mechanism formed of a number of independently operable sections, a revolute cam cylinder having needle-operating cams, and jacquard actuating means carried by the cam cylinder.

2. The combination with a knitting machine, of a jacquard mechanism divided into a plurality of independent and successively operable sections, a revolute cam cylinder having needle-operating cams and jacquard actuating mechanism movable with said cam cylinder.

3. A circular knitting machine having stationary needle

cylinders, needles and jacks therein, revolute cams, a jacquard or pattern mechanism, and an operating device therefor, revolute with the cams.

4. In a machine of the class described, the combination with the cylinders, needles and jacks, of needle operating cams a jacquard or pattern mechanism divided into sections, each section controlling an independent group of needles, and means carried by the cams for actuating the jacquard.

5. In a circular knitting machine, stationary cylinders, needles and jacks therein, revolute cams, a jacquard mechanism for controlling the needles, said jacquard mechanism being divided into successively operable sections, and jacquard actuating means carried by the cams.

6. A circular knitting machine having stationary needle cylinders, needles and jacks therein, revolute cams arranged to move corresponding upper and lower jacks to idle position, and a jacquard mechanism arranged to operate while the jacks are idle, and thus control the positions subsequently assumed by said jacks.

7. In a circular knitting machine, superposed needle cylinders, needles and jacks therein, auxiliary jacks in the upper cylinder and in part controlling the movement of the main jacks of said upper cylinder, and a pattern mechanism connected to said auxiliary jacks.

8. In a circular knitting machine of the class described, upper and lower stationary needle cylinders, jacks and needles supported thereby, a cam ring having a cam member arranged to move all of the jacks of one cylinder to a position beyond the control of the remaining portion of the cam, and a jacquard mechanism for determining the jacks to be readjusted to operative position.

9. In a circular knitting machine of the class described, a pair of superposed needle cylinders, needles and jacks therein, a cam arranged to move one set of jacks to idle position, auxiliary jacks, a restoring cam arranged in position to engage the auxiliary jacks and through the latter restore the idle jacks to operative position, and a pattern mechanism for moving said auxiliary jacks out of the path of the restoring cam.

10. In knitting machine of the class described, superposed needle cylinders, needles and jacks therein, revolute cam rings, a pattern mechanism, auxiliary jacks arranged in the upper cylinder and adapted to engage the upper jacks, a restoring cam for engaging the auxiliary jacks, and means connecting the auxiliary jacks to the pattern mechanism, whereby said auxiliary jacks may be raised beyond the path of movement of the needle jacks.

11. The combination with a circular knitting machine, of a jacquard mechanism, said mechanism being divided into sections each complete in itself and including a card cylinder and jack needles, and means for successively operating the sections of said jacquard mechanism.

12. In a knitting machine of the class described, superposed needle cylinders, needles and jacks therein, a pair of revolute cam rings, the cams of both rings being arranged to move the aligned jacks of the upper and lower cylinders to idle position, a series of auxiliary jacks arranged in the upper cylinder, a restoring cam for engaging the auxiliary jacks and transmitting movement through said auxiliary jacks to the main jacks of the upper cylinder, a pattern mechanism, an operating means therefor, revolute with the cam rings, said mechanism being divided into independently and successively operable sections, means for connecting the pattern mechanism to the auxiliary jacks, and a cam carried by the cam ring and serving to move all of the jacks to initial position once during each revolution of the cam rings.

In testimony whereof I affix my signature, in presence of two witnesses.

HEINRICH STOLL, Jr.
